UNITED STATES PATENT OFFICE.

HENRY BESANCON, OF STEPHEN, MINNESOTA.

MOTOR-DRIVEN POST-HOLE DIGGER.

1,243,580.

Specification of Letters Patent. Patented Oct. 16, 1917.

Application filed July 20, 1917. Serial No. 181,777.

To all whom it may concern:

Be it known that I, HENRY BESANCON, a citizen of the United States, residing at Stephen, in the county of Marshall, State 5 of Minnesota, have invented a new and useful Motor-Driven Post-Hole Digger; and I do hereby declare the following to be a full, clear, and exact description of the invention, such as will enable others skilled in the art 10 to which it appertains to make and use the same.

The present invention relates to a power driven post hole digger, and has for its object to provide a device of this character 15 which embodies novel features of construction whereby it can be readily mounted upon a truck so as to be easily moved from place to place, and which will operate in a quick and economical manner to bore holes 20 in the ground of a suitable size and depth to receive a fence post or the like.

Further objects of the invention are to provide a post hole digger which is comparatively simple and inexpensive in its construction, which can be easily moved from place to place, which can be easily controlled by a single operator, and which can be quickly adjusted and set in proper position for boring a hole in the ground.

With these and other objects in view, the invention consists in certain novel combinations and arrangements of the parts as will more fully appear as the description proceeds, the novel features thereof being 35 pointed out in the appended claims.

For a full understanding of the invention, reference is to be had to the following description and accompanying drawing, in which:—

40 Figure 1 is a rear elevation of a post hole digger constructed in accordance with the invention, the engine being omitted to avoid confusion.

Fig. 2 is a top plan view of the post hole 45 digger, the upper portion of the vertical frame being broken away and removed to bring out more clearly the details of construction.

Fig. 3 is an enlarged detail view of the 50 auger and dirt deflecting shield, portions being broken away and shown in section.

Corresponding and like parts are referred

to in the following description and indicated in all the views of the drawings by the same reference characters.

Specifically describing the present embodiment of the invention, the reference character A designates a truck which may be of any conventional construction and is mounted upon the wheels 1 so as to be conveniently moved from place to place. An engine 2 of a suitable character is mounted upon the platform of the truck and arranged to be employed for driving the earth boring auger. An arched upright frame 3 is arranged at the rear end of the truck A, being shown as mounted upon the projecting ends of the longitudinal beams 4 which extend under the platform. A pair of sleeves 5 are journaled in the top of the arched frame 3 and in a cross bar 7 connecting the sides of the arched frame, said sleeves being formed with square openings which slidably receive a square shaft 7. This shaft 7 is vertically disposed and provided at its lower end with an auger 8 which is adapted to be used for boring a hole of a suitable diameter and depth in the ground. The lower sleeve 5 is connected by bevel gearing 9 to a horizontal drive shaft 10 which is journaled 60 within suitable bearings 11 on the upright frame, and provided at its projecting end with a drive pulley 12. A belt 13 connects the pulley 12 of the drive shaft 10 to the pulley 14 of the engine shaft, so that when the engine is in motion the drive shaft 10 will be rotated and the sleeve 5 driven. The vertical shaft 7 is slidable freely up and down through the sleeves 5, but is rotatable with the lower sleeve 5, owing to its polygonal formation, so that the shaft and auger 65 are positively driven by the shaft 10 which receives power from the engine 2.

A collar 15 is rigid with the shaft 7 and projects laterally therefrom, said collar being engaged by a forked arm 16 projecting from a sliding rack 17. A vertically disposed guideway 18 receives the rack 17 and directs it in its up and down movements, the teeth of the rack being engaged by a pinion 19 on a short horizontal shaft 20 which is journaled within suitable bearings 21 and provided at its end with a hand wheel 22. With this construction it will be obvious

that by rotating the hand wheel and turning the pinion 19 the rack bar 17 can be moved up and down, carrying with it the polygonal shaft 7 and auger 8. This enables the 5 auger to be moved up and down into and out of operative position, and to be held to its work while the device is in operation.

A tubular guide casing 23 surrounds the auger 8 and is provided at the sides thereof 10 with a conical dirt deflecting shield 24, the dirt being discharged from the auger at the upper end of the tubular guide casing 23 and being deflected away from the opening by the shield 24 so that the loose dirt will 15 not fall back into the opening when it has been bored to the proper depth and the auger and shield are raised into inoperative position. Projecting laterally from opposite sides of the conical dirt deflecting 20 shield 24 are brackets 25 which are formed with balls 26, said balls being loosely engaged by sockets 27 at the lower ends of supporting rods 28. These rods 28 are vertically disposed, being slidably received 25 within guide keepers 29 projecting from the sides of the arched frame 3, and terminating at their upper ends in racks 30 which slide through guide openings 31 in the cross bar 6 of the upright frame. These rack 30 bars 30 are engaged by pinions 32 on a horizontal shaft 33 which extends across the upright frame 3, being journaled at the sides thereof, and is provided at one of its ends with a hand wheel 34. With this construction it will be obvious that by manipulating the hand wheel 34 to rotate the shaft 33 and pinions 32, the supporting rods 28 and dirt deflecting shield 24 can be moved up and down, thereby enabling the latter 40 to be readily raised and lowered into and out of operative position.

When the digger is not in operation the auger 8 and dirt deflecting shield 24 are raised upwardly above the surface of the 45 ground so that they will not interfere in any manner with the movements of the truck. The truck can then be moved from place to place without difficulty, and when the device is properly positioned at the 50 point where it is desired to dig a post hole, the dirt deflecting shield 24 and auger 8 are lowered into engagement with the ground and the motor started for the purpose of driving the auger. By suitably manipulating 55 the hand wheel 22 the auger can be forcibly held to its work, and a hole drilled to the desired depth in the ground. The earth which is loosened by the auger will be elevated to the upper end of the tubular guide 60 casing 23 and be discharged laterally therefrom, falling upon the conical shield 24 which will deflect it to one side and deposit it upon the surface of the ground at a distance from the opening which has just been 65 bored. This will prevent the loose earth

from falling back into the opening when the auger and dirt deflecting shield are again raised into inoperative position, preparatory to moving the device into proper position for boring another hole in the 70 ground.

Having thus described the invention, what I claim as new and desire to secure by Letters Patent, is:—

1. A post hole digger including an upright frame, a vertical auger shaft mounted upon the frame to have both a rotary and a sliding movement, an auger at the lower end of the shaft, means for driving the shaft, a collar rigid with the shaft, a rack 75 bar provided with a forked arm straddling the collar, a pinion meshing with the rack bar, means for rotating the pinion to raise and lower the rack bar which carries with it the auger shaft, a dirt deflecting shield 80 surrounding the auger for receiving the loose dirt discharged therefrom and deflecting it away from the opening, and means for raising and lowering the dirt deflecting 85 shield. 90

2. A post hole digger including an upright frame, a vertical auger shaft mounted upon the frame to have both a rotary and a sliding movement, an auger at the lower end of the shaft, means for driving the 95 shaft, means for raising and lowering the shaft, a tubular guide casing surrounding the auger and formed with a conical dirt deflecting shield for deflecting loose dirt discharged through the upper end of the guide 100 casing away from the opening, side brackets projecting from the dirt deflecting shield, upright supporting bars connected to the bracket and provided with racks, a transverse shaft journaled upon the upright frame and 105 provided with pinions meshing with the racks, and means for rotating the shaft and pinions to raise and lower the earth deflecting shield. 110

3. A post hole digger including an upright frame, a vertical auger shaft mounted upon the frame to have both a rotary and a sliding movement, an auger at the lower end of the shaft, means for driving the 115 shaft, means for raising and lowering the shaft and holding the auger to its work, a tubular guide casing surrounding the auger and provided at its sides with a conical dirt deflecting shield arranged to deflect the loose dirt discharged from the upper 120 end of the tubular casing away from the opening, side brackets projecting laterally from the deflecting shield, upright supporting rods having ball and socket connections at their lower ends with the side brackets 125 and provided with racks, guide members, engaging the supporting rods to direct them in their movements, a transverse shaft journaled upon the upright frame and provided with pinions which mesh with the racks, 130

and means for rotating the shaft and pinions to raise and lower the dirt deflecting shield.

4. A post hole digger including an upright frame, a pair of superposed sleeves journaled upon the frame and formed with polygonal openings, a polygonal shaft slideable through the sleeves and rotatable therewith, a horizontal drive shaft journaled upon the frame, gearing between the drive shaft and one of the sleeves, a collar projecting from the auger shaft, a vertically slideable rack bar arranged at one side of the shaft, a forked arm projecting from the rack bar and straddling the collar of the shaft, a pinion meshing with the teeth of the rack bar, means for rotating the pinion to raise and lower the auger shaft, an auger at the lower end of the shaft, and a dirt deflecting shield surrounding the auger for deflecting the loose dirt discharged therefrom away from the opening.

5. A post hole digger including an upright frame, a vertically disposed auger shaft mounted upon the frame to have a rotary and a sliding movement, an auger at the lower end of the shaft, means for driv-

ing the shaft, a collar projecting from the shaft, a vertically slideable rack bar arranged at one side of the auger shaft and 30 provided with a forked arm straddling the collar, a pinion meshing with the teeth of the rack bar, means for rotating the pinion to raise and lower the auger shaft, a tubular guide casing surrounding the auger and 35 provided with a conical dirt deflecting shield for deflecting the loose dirt discharged from the upper end of the tubular casing away from the opening, side brackets projecting from the dirt deflecting shield, 40 upright supporting rods connected at their lower ends to the side brackets and provided with racks, a transverse shaft journaled upon the upright frame and provided with pinions meshing with the racks, and 45 means for rotating the shaft to raise and lower the dirt deflecting shield.

In testimony whereof I have signed my name to this specification in the presence of two subscribing witnesses.

HENRY BESANCON.
